UNITED STATES PATENT OFFICE.

GEORGE W. TURNER AND JAMES A. WILES, OF DAYTON, OHIO, ASSIGNORS
OF ONE-THIRD TO FRANK BUNDY, OF SAME PLACE.

COMBINED MATCH-SAFE AND ADVERTISING DEVICE.

SPECIFICATION forming part of Letters Patent No. 612,936, dated October 25, 1898.

Application filed February 28, 1898. Serial No. 671,931. (No model.)

To all whom it may concern:

Be it known that we, GEORGE W. TURNER and JAMES A. WILES, citizens of the United States, residing at Dayton, in the county of 5 Montgomery and State of Ohio, have invented a certain new and useful Improvement in a Combined Match-Safe and Advertising Device; and we do hereby declare that the following is a full, clear, and exact description 10 of the invention, which will enable others skilled in the art to which it appertains to make and use the same; reference being had to the accompanying drawings, and to the letters of reference marked thereon, which form 15 a part of this specification.

Our invention relates to improvements in combined match-safes and advertising devices; and it consists in combining in a match-safe of special construction means for displaying advertising matter on a revolving drum, which is set in motion each time a match is discharged.

In the accompanying drawings, Figure 1 is a front elevation of our improved match-safe. 25 Fig. 2 is a top plan view with the drum removed. Fig. 3 is a sectional view on the line X X of Fig. 2. Fig. 4 is an enlarged plan view of the slide.

The case A contains a match-hopper A' 30 with a rearward-inclined wall A" and a front incline B, to the front of which the matches a are delivered. The rearward end of the incline B terminates in a horizontal wall B', and its front end projects out through a front off- 35 set A³ in the case.

C designates a match-delivery slide enclosed between the horizontal wall B', the lower edge of the incline A", and the top A⁴ of the offset A³, so that it is maintained in a 40 sliding position. The slide has a transverse match-slot C', into which the matches enter from the hopper, and as the slide is moved sufficiently forward to bring the slot to a position in advance of the front edge of the 45 wall B' the match drops upon the incline B.

At one side of the case there is a vertical slot D, through which a finger-lever D' is projected. This lever has its inner end fixed to a transverse shaft E, that is suitably journaled to 50 the sides of the case. From a central part of this shaft there is a rigid arm E', which has its upper end passed through an opening

F in the slide. It will be seen that upon each downward movement of the finger-lever D' the slide will be moved forward to deliver a 55 match. Its return is effected through the contraction of a coil-spring G, which is secured to the arm E' and to a transverse stationary bar G'. The drum or cylinder H is rotated upon each operation of the slide through 60 mechanism presently described. This cylinder may be constructed of any suitable light material—such as cardboard, sheet metal, &c.—and provides space for the display of advertising matter, the vertical bands H' affording means for supporting cards, &c. The cylinder is supported on a vertical shaft I above the casing and free from any contact therewith. The shaft I is journaled in transverse bars J and G' and has fixed to its lower 70 end a ratchet-wheel J', which is intermittently rotated by a pawl K, the engaging end of which rests upon the teeth of the wheel. The said pawl is loosely mounted on the slide C by having one end passed through an opening c in the said slide. L is an opening for the tip of a cigar and constituting, in connection with the knife-edge L' on the slide, a cigar-cutter.

Having described our invention, we claim— 80

A combined match-safe and advertising device, comprising a stationary hopper, a slide movable below said hopper and adapted to deliver matches therefrom—a stationary support below said slide, an upright rotatable 85 shaft in the rear of said slide, a ratchet-wheel, and a display-cylinder mounted on said shaft, a pawl secured to the rear of said slide and engaging with said wheel, a rotatable shaft below said slide, an arm projecting 90 therefrom and connecting with the slide, a finger-lever connected to said shaft, and a resetting-spring normally controlling the said finger to maintain the slide in a rearward position, substantially as and for the purpose 95 specified.

In testimony that we claim the foregoing as our own we affix our signatures in presence of two witnesses.

GEORGE W. TURNER.
JAMES A. WILES.
